CARTRIDGE CLIP

John C. Garand, Springfield, Mass.

Application August 27, 1941, Serial No. 408,479

2 Claims. (CL. 42—88)

(Granted under the act of March 3, 1883, as
amended April 30, 1928; 370 O. G. 757)

The invention described herein may be manufactured and used by or for the Government for governmental purposes, without the payment to me of any royalty thereon.

The subject of this invention is a cartridge clip of the type shown in my U. S. Patent 2,121,792 and intended to hold a double row of cartridges in staggered relation and to be inserted therewith into the receiver of a gun.

The purpose of this invention is to provide the back plate of the clip with ribs forming rails for the base of the cartridges and to provide the side walls with outwardly directed ribs adjacent the inwardly directed ribs at the forward edge of the side walls.

The specific nature of the invention as well as other objects and advantages thereof will clearly appear from a description of a preferred embodiment as shown in the accompanying drawing in which:

Fig. 1 is a bottom plan view of the cartridge clip;

Figs. 2 and 3 are sectional views on the corresponding lines of Fig. 1.

Referring to the drawing by characters of reference, the clip consists of a back plate 5 and spring-pressed side walls 6—6 which converge forwardly and are formed with inwardly curved ends 7—7. The side walls adjacent the back plate have outwardly extending ribs 8—8 which serve to guide the clip into the receiver of a gun and hold it in position therein, fitting into grooves in the receiver for such purpose, and also inwardly extending beads or ribs 9—9 which engage in front of the extracting rims A of the cartridges B and retain them in position in the clip.

As shown in the patent the back plate is provided with generally transversely extending arculate ribs 10 which stiffen the plate and are so formed as to resist distortion of the clip due to the staggered or diagonal position of the cartridges loaded in the clip.

At the forward edge of each side wall 6 an inwardly pressed rib 11 is provided to reduce frictional contact of the cartridges with the side wall and thereby relieve the follower of the gun of considerable effort in elevating the cartridges to feeding position.

The elements thus far described are all present in the clip of the patent. By reference to Fig. 3 of this application it will be noted that the guide ribs 8 provide an internal channel or groove 12 whose width is substantially twice the thickness of the rim A of the cartridge. The

dimension of the groove is identical with that of the patent and is established in forming the guide rib without decreasing the bending radius beyond a value which impairs the inherent resiliency of the side walls 6—6. As a consequence of the excessive width of the groove 12, cartridges may be loaded in the clip of the patent with unequal longitudinal positioning and overlapping rims and with improper bearing contact with the side walls. Furthermore some of the cartridges will have their bases riding on the back plate whose surface is roughened by the stiffening ribs 10 and may be covered with dirt.

In order to eliminate the foregoing objections the back plate is provided with a plurality of inwardly projecting and longitudinally extending preferably parallel rails or ribs 13—13 although it will be understood that the ribs may be arranged in other than parallel relation. While

only two ribs are shown and suffice for the purpose it is obvious that additional ribs might be provided. The ribs 13, (which also serve to stiffen the back plate) are formed by deforming the metal of the back plate by pressing it inwardly from the outside. As shown in Fig. 1 the ribs 13, laterally define the stiffening ribs 10 and as seen in Fig. 3 they are spaced laterally a slight distance from the ribs 9.

The ribs 10 project inwardly towards the rib 9 an amount which is predetermined to allow just sufficient space to accommodate the rim A of the cartridge. By virtue of this arrangement the portion of the cartridge directly in front of the cannelure will have a substantial bearing on the side wall 6. The rims of all of the cartridges in the stack will lie in the same plane and elevation of the stack by the follower of the gun will be facilitated. The spacing of the bases of the cartridges from the back plate prevents interference with the movement of the stack by dirt or sand which may have accumulated on the back plate and also facilitates removal of the sand from a loaded clip.

In double-row en bloc clips of this type the full stack of cartridges is normally held against removal by the pressure exerted by the side walls. When the clip is in a gun the feeding of the first or uppermost cartridge from the clip to the gun barrel would result in the removal of the pressure of the side walls on the stack except for the action of the follower of the gun which elevates the remainder of the stack. However when only two cartridges remain in the clip the pressure of the follower

may readily cause jamming or crossing of these two cartridges because the front portions of the side walls 6—6 may spread. In order to eliminate this disadvantage the side walls 6—6 are provided with an outwardly directed rib 14 which is parallel to and adjoins the rib 11. The ribs 14 in addition to serving as stiffeners have the function of engaging the walls of the receiver of the gun and prevent spreading of the side walls 6 and jamming of the cartridges.

Because of the taper of the cartridges the distance between the ribs 11—11 of a loaded clip is considerably less than the distance between the guide ribs 8—8. Since the sides of the receiver are parallel the provision of the ribs 14 eliminates the loose fit of the clip in the receiver and maintains the side walls against spreading beyond their normal cartridge compressing position. The distance between the ribs 14—14 is only slightly less than the distance between the 20 guide ribs 8—8.

I claim:

1. A clip for holding a double row of car-

tridges in staggered relation comprising a back plate and side walls, inwardly and longitudinally extending ribs in the back plate adjacent the side walls, oppositely disposed longitudinally and outwardly extending guide ribs adjacent the back plate and inwardly and longitudinally extending heads at the juncture of the guide ribs and side walls, the beads adapted to enter the groove at the base of the cartridges, the said ribs and beads cooperating and acting upon one side of the cartridge base to hold the bases of said cartridges in alignment and support them above the major portion of the interior of the back plate.

2. The cartridge clip as claimed in claim 1 characterized in that the side walls of the clip adjacent the front edges thereof are each provided with an outward and horizontally extending rib arranged to contact with the sides of the receiver of the gun to prevent the side walls from spreading beyond their normal cartridge compressing position.

JOHN C. GARAND.

CERTIFICATE OF CORRECTION.

Patent No. 2,338,107.

January 4, 1944.

JOHN C. GARAND.

It is hereby certified that error appears in the printed specification of the above numbered patent requiring correction as follows: Page 2, second column, line 7, claim 1, for the word "heads" read --beads--; and that the said Letters Patent should be read with this correction therein that the same may conform to the record of the case in the Patent Office.

Signed and sealed this 8th day of August, A. D. 1944.

Leslie Frazer
